METAL RADIANT FOR GAS HEATERS

Filed July 22, 1948

UNITED STATES PATENT OFFICE

2,474,169

METAL RADIANT FOR GAS HEATERS

Roy Shelton, Chattanooga, Tenn., assignor to
 Samuel Stamping and Enameling Company,
 Chattanooga, Tenn., a corporation of Tennessee

Application July 22, 1948, Serial No. 40,049

2 Claims. (Cl. 126—85)

1

This invention relates to gas heaters.

The invention is more particularly concerned with an improved radiant construction for removable disposition over a gas burner in a suitable stove construction.

A primary object of the invention is the provision of a sheet metal radiant of cylindrical form for vertical disposition over a gas burner suitably arranged in a stove body.

A further object of the invention is to provide an elongated sheet metal cylindrical radiant having a multiplicity of relatively small apertures in the wall thereof, and the radiant having supporting means for removable disposition over a gas burner with its lower end in vertical spaced relation thereto.

A still further object of the invention is to provide a radiant in the form of a cylindrical shell constructed of stainless steel and which is capable of expeditious manufacture and is capable of long use while at the same time being capable of radiating a maximum of heat.

Other objects and advantages of the invention will become apparent in the course of the following detailed description taken in connection with the accompanying drawing, wherein—

Fig. 1 is a substantially vertical axial section through the improved stove with one of the front sliding doors being partially shown in front elevation.

Fig. 2 is a horizontal sectional view in the plane of line 2—2 on Fig. 1 and on a reduced scale.

Fig. 3 is a horizontal sectional view in the plane of line 3—3 on Fig. 1 and on a reduced scale.

Fig. 4 is an axial vertical section of the upper portion of the incandescent member or radiant.

While the body of the stove including the outer shell may be of various forms, a desired construction for use of the improved radiant or incandescent member comprises a suitable circular base 10 provided with supporting legs 11.

The upper end of the base is suitably rolled or otherwise formed to provide an inner vertical flange 12 and a curved portion providing in combination with flange 12 a circular track 13.

The outer shell may desirably comprise a rear semi-cylindrical portion 14 and a pair of foraminous sliding front doors 15, both of which are shown closed in Fig. 3 and only one of which is shown partially closed in Fig. 1.

The outer shell further comprises a circular upper portion 16 having a vertical flange 17 and a circular track 18.

The rear portion is suitably secured to flanges 12 and 17 and the doors are slidably supported

2

at their lower and upper edges in the tracks 13 and 18.

The upper portion 16 includes an inwardly directed horizontal flange 19 to which is secured 5 the horizontal flange 20 of a drum member 21 which is provided with suitable openings 22 throughout its circumference.

A cover member 23 is removably supported on drum member 21 and is provided with a circumferential series of openings 24 in its otherwise closed top wall 25.

A burner 26 is disposed in an aperture 27 in a plate 28 suitably secured to flange 12. The burner may be supported in position by a bracket 29 suitably secured to the bottom of plate 28.

A circular baffle plate 30 is supported within drum member 21 adjacent the top thereof as by means of legs 31 whose lower ends rest upon and are suitably secured to flange 19.

An important feature of the present invention resides in the improved metal radiant or incandescent member 32. It is preferably formed of stainless steel and is stamped out, perforated, and bent to proper form. This member is disposed axially of the outer shell including portions 14 and 15, and it is disposed vertically as indicated in Fig. 1.

The member 32 is in the form of a cylindrical shell which is open at its lower end and closed 30 by a flanged disk 33 at its upper end and the cylindrical wall of the shell is provided with a multiplicity of small apertures 34.

The shell 32 is provided with a tongue 35 at its upper end and which is rigidly supported on the cylindrical wall thereof.

The tongue 35 is provided with an aperture 36 for removably receiving a hook 37 depending from and suitably secured to the baffle plate 30.

The tongue and hook provide a suspension for 40 the shell 32 with its open lower end disposed a relatively short distance above the burner 26 as is indicated in Fig. 1.

The lower end of the shell is provided with a pair of diametrically disposed legs 38 insertable 45 in openings 39 in the plate 28 for maintaining the shell in proper vertical position above the burner 26.

It is to be particularly noted that the member 32 has its lower end in substantial spaced relation to the burner 26 whereby providing for admission of air to the inside of the radiant which is necessary for complete combustion of the gases.

While I have disclosed my invention in accordance with a single specific embodiment thereof,

such is to be considered as illustrative only and not restrictive, the scope of the invention being defined in the subjoined claims.

What I claim and desire to secure by U. S. Letters Patent is:

1. In a gas heating stove including a generally cylindrical vertical wall and a top cover, a horizontally disposed burner supported substantially axially of said wall and adjacent the bottom thereof; a sheet metal cylindrical radiant disposed over said burner in substantially coaxial relation to said wall, and means for removably securing the radiant within the stove, said stove including a horizontally disposed baffle adjacent said top cover and a horizontally disposed plate adjacent the bottom of the wall, said means comprising a cooperating hook and tongue on the baffle and radiant for suspending the latter from the baffle, and said means further comprising a pair of legs depending from the lower end of the 15 radiant and removably received in apertures in said plate.

2. A radiant for use in gas heating stoves comprising a sheet steel cylinder provided with apertures in the wall thereof, one end of said cylinder being open for disposition over a gas burner and a flanged disk closing the other end of the cylinder, together with supporting means on the radiant comprising an apertured tongue adjacent said disk and a pair of legs adjacent the open end of the cylinder.

ROY SHELTON.
